Des. 70,950

UNITED STATES PATENT OFFICE.

NORMAN V. CHRISTENSEN AND HAROLD J. LE VESCONTE, OF CHICAGO, ILLINOIS,
ASSIGNORS TO UNION SPECIAL MACHINE COMPANY, OF CHICAGO, ILLINOIS, A
CORPORATION OF ILLINOIS.

DESIGN FOR A SEWING-MACHINE FRAME.

Application filed July 1, 1924. Serial No. 10,018. Term of patent 14 years.

To all whom it may concern:

Be it known that we, NORMAN V. CHRISTENSEN and HAROLD J. LE VESCONTE, citizens of the United States, residing at Chicago, in the county of Cook, State of Illinois, have invented certain new, original, and ornamental Design for Sewing-Machine Frames, of which the following is a description, reference being had to the accompanying drawing, forming a part thereof.

Figure 1 is a perspective view; and

Figure 2 is an end view looking toward the position occupied by the operative.

We claim:

The ornamental design for a sewing machine frame, substantially as shown and described.

In testimony whereof, we affix our signatures.

NORMAN V. CHRISTENSEN.
HAROLD J. LE VESCONTE.
